UNITED STATES PATENT OFFICE.

CHARLES Y. KNIGHT, OF CHICAGO, ILLINOIS, ASSIGNEE, BY MESNE ASSIGNMENTS, TO
KNIGHT AMERICAN PATENTS COMPANY, A CORPORATION OF DELAWARE.

INTERNAL-COMBUSTION ENGINE.

1,136,143.

Specification of Letters Patent. Patented Apr. 20, 1915.

Application filed October 10, 1908. Serial No. 457,057.

To all whom it may concern:

Be it known that I, CHARLES Y. KNIGHT, a citizen of the United States of America, residing at 154 Lake street, in the city of Chicago, county of Cook, and State of Illinois, having invented certain new and useful Improvements in Internal-Combustion Engines, of which the following is a specification.

- 10 This invention relates to that type of internal combustion engines or motors in which fluid admission to and exhaust from the explosion space is controlled by port controlling provisions embodying a cylindrical port controlling element operatively connected with the working piston and being thereby moved with relation to the outer or main cylinder for opening and closing the ports therein.
- 20 It has more special reference to the modern form of such motors in which said port controlling provisions embody two of said cylindrical port controlling elements or sleeves, telescoped together around the working piston and having ports which coincide at the proper times during the cycle of the engine. In engines of this type as heretofore constructed, the sleeves have been provided with two exhaust 30 ports adapted to register respectively with two exhaust ports located in the outer cylinder at opposite ends thereof, so that a part of the burned gases will escape as the piston nears the limit of its outward 35 stroke and uncovers the outer one of these exhaust ports, and the balance will escape when the piston starts back again and the ports in the sleeves at the opposite end become properly adjusted. One of the serious 40 defects of such prior means for controlling the exhaust is, that the blow-pipe action of the burning gas, passing through the lower or terminal exhaust port, excessively overheats the sleeves on the side adjacent such 45 ports, and causes them to warp out of round, also to blister as the inner one is in direct contact with the flame and does not come in contact with a water-cooled surface at this point. It also causes the piston to warp 50 out of round as a result of the blow-pipe action of the flame crossing the piston at one side only. In addition, it causes the inner sleeve to expand and elongate on the exhaust side, (half way around the sleeve) a much greater extent than does the outer one which 55 is in contact with the water-jacket—the inner sleeve thereby getting out of line with the outer one. This results in seizure or severe friction of the inner sleeve which should, in practice, be free from the outer 60 sleeve by a space of from one to two thousandths of an inch, so that a film of oil will remain between the sleeves to furnish a packing and relieve wear. At the upper or inner end of the sleeves these conditions 65 do not obtain because the construction permits of bringing both sleeves adjacent the exhaust port, in direct contact with water-cooled surfaces after such exhaust stroke. Such prior method of controlling the exhaust 70 also results in serious lubrication trouble. The exhaust, being admitted at high pressure between the sleeves where the lower or terminal exhaust port is cut through, drives the oil from between the 75 sleeves in both directions (upward and downward), and burns it, thereby depriving the sleeves of proper lubrication at their lower ends half way around and at the hottest locality and at the very place where an 80 abundance of lubricant is required. The oil thus expelled takes fire and is shot down into the crank case, burns the lubricant there and overheats the bearings. The portion which is driven upwardly is expelled 85 through the upper exhaust port, when the latter opens at a later period, and this, together with that which is driven out through the lower exhaust port by the direct and entraining action of the escaping gases, causes 90 a seriously smoky exhaust and a waste of valuable lubricant. This expulsion of the lubricant from between the sleeves at their lower ends, results in depriving the sleeves 95 of sufficient lubricant at their upper ends also, because as practice has demonstrated with this type of engine, the best method of lubricating the sleeves is to allow the oil to feed upwardly between them from the crank case as the result of capillary attraction or 100 the suction due to the inspiration stroke of the piston causing some compression in the crank case and a rarefaction of the fluid between the sleeves adjacent the upper exhaust port, thereby creating two forces favorable 105 to an upward flow of oil between the sleeves which would be counteracted by the admission of the exhaust gases between the sleeves

near their lower ends, as when the lower or terminal exhaust port is employed. This result does not follow however where the upper exhaust port alone is employed, because it is so far removed from the lower ends of the sleeves that the exhaust gases cannot find their way through the long capillary passage between the sleeves in sufficient volume to seriously interfere with the upward trend of the oil.

This invention therefore is designed to overcome these defects of the described type of internal combustion motors, and it has for one of its objects to provide an improved motor of this type in which the exhaust takes place wholly at the firing or intake end of the cylinder. In this type of internal combustion motors, the aforesaid cylindrical port controlling element is thin to permit the heat to radiate through to the water-jacket of the outer cylinder. At the period of exhaust however, the edges of said element are subjected to the blow-pipe action of the burning gases and such edges are thus liable to be seriously burned, resulting in rough surfaces and in irregular port opening and other obvious defects.

The invention is designed to avoid these defects also, and has for another object to improve the cooling facilities of the sleeves adjacent the exhaust ports thereof.

With a view to the attainment of these ends and the accomplishment of certain other objects which will hereafter appear, the invention consists in the features of novelty described herein, shown in the accompanying drawings and more particularly pointed out in the claims.

Referring to the accompanying drawings:—Figure 1 is a sectional elevation of the engine cylinder, Figs. 2 and 2^a are views showing the position of the ports at four points of the cycle.

In the form shown in Fig. 1, suitable for a petrol engine working on the ordinary four stroke cycle, I construct the straight part, *a*, of the cylinder with a water jacket, *b*, along its whole length, and form the inlet and exhaust ports, *c*, *d*, respectively through the water jacket at the combustion chamber end or intake end of the straight part, *a*, of the cylinder. The end of the cylinder is closed by a water cooled head, *e*, having a water cooled part, *f*, projecting internally, forming a groove, *g*, with the straight part of the cylinder. In this groove the ends of sleeves, *h*, *k*, slide. These sleeves the outer one of which need not completely surround the inner are provided with ports, *m*, *n*, and *o*, *p*, adapted to register with the ports, *c* and *d*, respectively in the cylinder at parts of their movement for the purpose of obtaining the inlet and exhaust to the cylinder as hereinafter described. The head *e* constitutes a cylindrical port controlling element

telescoped with the inner sleeve for controlling the ports therein and the sleeves constitute cylindrical port controlling elements arranged coaxial with the fixed cylinder and piston and surround the latter and the explosion space in which the piston reciprocates, for coöperating with the head and fixed cylinder to control fluid admission to and exhaust from the said explosion space. The sleeves *h*, *k*, are actuated by means of a pair of eccentrics, *r*, *s*, one of which operates the outer sleeve, *h*, while the other operates the inner sleeve, *k*. The eccentric *r*, in this form is placed 90 degrees ahead of the other eccentric *s*. Rings, *t*, are provided in the internal projection, *f*, from the head of the cylinder, and bear against the inner sleeve, *k*, forming a gas tight sliding contact. The eccentrics actuating the sleeves rotate once every two revolutions of the main shaft.

The cycle of operation of the engine is as follows:—Supposing an explosion has taken place in the engine, and the piston is moving on its working stroke from the position shown at A Fig. 2, when the piston has moved to within about 50 degrees of the end of its out stroke, the port, *n*, in the outer sleeve, *h*, is almost in register with the port, *d*, in the fixed cylinder, but is still moving slowly upward, while the inner sleeve, *k*, is moving downward rapidly as shown at B Fig. 2. The port, *p*, in the inner sleeve, *k*, quickly passes the edge, *u*, of the water cooled projection, *f*, on the head of the cylinder, opening a straight way through exhaust passage through the two sleeves and the cylinder. During the rapid downward movement of the inner sleeve, *k*, the outer sleeve, *h*, passes its dead center and begins to move slowly downward. When the piston has moved through about 90 degrees from its out center on the exhaust stroke, the downward movement of the outer sleeve, *h*, becomes rapid, quickly reducing the opening for exhaust, until it cuts off the exhaust at the cylinder edge, *v*, which is water cooled, just after the piston has passed its in center, the inner sleeve, *k*, during this period having passed its lowest position, and begun moving slowly upward as shown at C, Fig. 2^a. The rapid downward movement of the outer sleeve, *h*, also brings the inlet port, *m*, in that sleeve into register with the inlet port, *c*, in the cylinder, the inlet port, *o*, in the inner sleeve, *k*, in its lowest position being nearly in register with the inlet port in the cylinder. The straight through inlet is thus open to practically its fullest extent when the piston is in the middle of its downward stroke. At this position the upward movement of the inner sleeve, *k*, is at its greatest velocity, quickly cutting off the inlet, the cut off being effected by the travel of inlet port, *o*, over wide head ring, *t*, after the piston has passed its out center as shown

at D Fig. 2^a. The compression stroke then commences, the inner sleeve, *k*, moving slowly to its upper position, while the outer sleeve *h*, moves upward. At the end of the compression stroke the outer sleeve is moving rapidly upward, while the inner sleeve just reaches its highest position coming back to the position shown at A Fig. 2. During the explosion stroke, the exhaust port in the outer sleeve moves down into position to register with the exhaust port in the inner sleeve which is gradually moving downward, its velocity increasing to rapidly open the through exhaust passage as above described.

Having now described my invention what I claim as new and desire to secure by Letters Patent is:—

1. The combination of an engine cylinder having an exhaust port therein; a fixed member to coöperate therewith; two port-controlling members each having an exhaust port therein; and means adapted to operate said port-controlling members and move the lower edge of the exhaust port of one of said members over the lower edge of the fixed member to open the exhaust port of the engine, and to move the upper edge of the exhaust port of one of said members over the lower edge of the exhaust port of the cylinder to close the exhaust port of the engine.
2. The combination of an engine cylinder having intake and exhaust ports therein; a fixed member to coöperate therewith; two concentric sleeves slidably mounted in said cylinder and each having an intake and an exhaust port therein; a piston operatively mounted in the inner of said sleeves; and a connection between said sleeves and said piston moving the lower edge of the exhaust port of the inner sleeve downwardly over the lower edge of the fixed member to open the exhaust port of the engine, and moving the upper edge of the exhaust port of the outer sleeve over the lower edge of the ex-

haust port of the cylinder to close the exhaust port of the engine.

3. The combination of an engine cylinder having an exhaust port therein; a head on said cylinder and having a portion extending into said cylinder and spaced therefrom; two port-controlling members mounted in the space between said projection and the cylinder, disposed over said exhaust port and each having an exhaust port therein; and means operating said members and moving the lower edge of the exhaust port of one of said members over the lower edge of said projection to open the exhaust of the engine and moving the upper edge of the exhaust port of the other of said members over the lower edge of the exhaust port of the cylinder to close the exhaust port of the engine.

4. The combination of an engine cylinder having intake and exhaust ports therein; a head on said cylinder and having a portion extending concentrically into said cylinder and spaced therefrom; two telescoped sleeves mounted in said cylinder and extending into the space between the cylinder and said projection, each of said sleeves having an intake and an exhaust port therein; a piston mounted in said sleeves; and a connection between said piston and said sleeves moving the lower edge of the exhaust port of the inner sleeve downwardly over the lower edge of said projection to open the exhaust of the engine, and moving the upper edge of the exhaust port in the outer sleeve over the lower edge of the exhaust port of the cylinder to close the exhaust of the engine.

In testimony whereof I have signed my name to this specification in the presence of two subscribing witnesses.
